UNITED STATES PATENT OFFICE.

JOHN LA GATTA, OF NEW YORK, N. Y., ASSIGNOR TO ROBT. H. INGERSOLL & BRO., OF NEW YORK, N. Y.

DESIGN FOR A DISPLAY-FIXTURE.

44,560.

Specification for Design.

Patented Aug. 26, 1913.

Application filed May 9, 1912. Serial No. 696,245. Term of patent 14 years.

To all whom it may concern:

Be it known that I, JOHN LA GATTA, a subject of the Kingdom of Italy, and resident of New York, in the county of New York and State of New York, have invented a new, original, and ornamental Design for Display-Fixtures, of which the following is a specification, reference being had to the accompanying drawing, forming part thereof.

The figure is a front elevation of a display fixture showing my new design.

I claim:

The ornamental design for a display fixture, as shown.

JOHN LA GATTA.

Witnesses:

O. M. GOGE,
A. S. TRACY.
